(57) **CLAIM**

The ornamental design for a vacuum hose coupler, as shown and described.

DESCRIPTION

FIG. 1 is a front perspective view of a vacuum hose coupler in closed condition showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front view thereof;

FIG. 7 is a rear view thereof;

FIG. 8 is a front perspective view of the vacuum hose coupler in open condition;

FIG. 9 is a right side elevation view of FIG. 8;

FIG. 10 is a left side elevation view of FIG. 8;

FIG. 11 is a top plan view of FIG. 8;

FIG. 12 is a bottom plan view of FIG. 8;

FIG. 13 is a front view of FIG. 8;

FIG. 14 is a rear view of FIG. 8; and,

FIG. 15 is a rear perspective view of FIG. 8.
